ABSTRACT: Looms are fed with a thread or yarn from a tubular knitted tube of the yarn with thread unraveling from its end and hence under insignificant back tension. The tube can be pulled up by the pull on the yarn or preferably a portion is advanced to avoid any back tension. When the yarn has been unraveled from the length of tube advanced, another short length is advanced.

A preferred form of advancing mechanism is described in which the yarn tube moves between a metallic finger and a conducting surface. When the predetermined length of tube is advanced it insulates the two contacts and no further advancing takes place until the yarn from the tube has been unraveled back to the point where the finger contacts the conductive surface. This starts a motor turning two rolls which advance a certain length of tube and the motion of the roll ceases when a cam on the shaft of one of the rolls opens a microswitch. The advanced portion of the tube remains until it has again been unraveled back to the point where the contact is made as described above.

The feed is useful for any types of looms which obtain part or all of their weft threads from an external source. Typical examples of this type of loom are looms which use gripping or bullet shuttles and catch thread looms. Similarly most knitting machines draw their yarn or thread from an external source and the described stocking feed is useful on such machines also.

THREAD FEEDING DEVICE AND PROCESS

BACKGROUND OF THE INVENTION

There are a number of fabric making machines which receive thread or yarn from an external source or, in some cases, several external sources. Typical examples are looms which use gripping or bullet shuttles, such as for example the looms described in the Pfarrwaller Pat. Nos. 2,589,429 and 3,076,483; catch thread looms, such as described in the Fischer Pat. No. 671,820; and most knitting machines. In each case the thread or yarn is supplied from an external source and not from the quill in a shuttle, as in the ordinary type of shuttle loom. It will be noted that in a catch thread loom, while there is a shuttle with a quill, the thread or yarn from the quill serves only to catch and pull across double picks of an externally supplied thread in the form of a loop. The amount of thread from the shuttle is a minute portion of the total length of weft thread, serving only to pull the weft across and to bind one or more edges of the resulting fabric.

In all of the machines referred to, the feed of the thread from an external source presents a problem. It is usually desirable that the thread be fed under uniform and preferably quite low back tension. With hard threads or yarns which are substantially inelastic, the problem is not too serious, and yarn wound on cones or in packages has been practically used. However, when dealing with certain other types of yarn, such as for example elastic yarn, and especially core spun elastic yarn in which the elastic core is spun with staple or filament, yarns which are soft, bulky, and fluffy, and other similar types of yarn, they are not conveniently handled in the ordinary yarn packages. For example, with elastic yarns, and especially core spun elastic yarns, either the yarn has to be wound on a relatively soft package or wound on a hard bobbin under considerable tension. In either case a serious problem results, especially when the yarn packages or other form in which they are wound cannot be fed to the fabric making machines immediately or very shortly after winding. If there is considerable storage, elastic yarns tend to take a permanent set, which is not uniform if they are wound tightly, or they may shrink and distort relatively soft yarn packages, which presents problems of nonuniform tension, snarling, and the like when the yarn is fed to the fabric making machine.

Even with hard, inelastic textile yarns, problems are presented when the yarn has to be dyed in different colors. Unless the yarn is dyed carefully in skein form and then wound into packages, uniformity of dyeing often suffers. For example, in a package where the yarns cross over each other a dye bath may not bathe the yarn uniformly at such points and this may result in the so-called crossover problem, where the dyeing at these points is not as deep as in the remainder of the yarn. It is normally considered economically very advantageous to dye yarns in package form. However, in a number of cases, as pointed out above, this raises problems of uniformity and the like. Another problem which, though not as serious, is still a drawback in fabric making results when a number of different colors or textures of yarn are to be used in the same fabric; for example, if there are to be a number of different weft threads, either of different colors, different textures, or both, packages on which yarn may be wound can be somewhat bulky, and the space taken sometimes creates problems. It is true that the packages may be situated at quite a distance from the point where the yarns are actually fed into the fabric making machine, but this requires the unwound yarn to travel over a considerable distance, increasing the possibilities of snarling, nonuniform tension, and the like.

SUMMARY OF THE INVENTION

Essentially, the present invention forms the yarn or thread to be fed to the fabric making machine in the form of a knitted tube. When the end of the tube is presented to the fabric making machine, the thread or yarn is unraveled from the end under perfectly uniform and relatively low tension. The tube is a compact form in which a very long length of yarn, miles in

some cases, can be knit and the tube is readily shipped. Ordinarily the shipping is in boxes in which the tube is folded, and as one end is pulled out the tube unfolds for the next fold. The cost of knitting the tube is quite low as knitting can proceed at very fast speed because precision knitting is not required. The cost of high speed knitting of the tube may often be little, if any, higher than the cost of winding in packages or on bobbins; and when the savings and improved quality of dyeing is taken into consideration, the overall cost is ordinarily considerably lower. It should be noted that the yarn in the tube is not under high tension and it can be stored indefinitely, even if the yarns are elastic yarns, such as core spun yarns, and the problems of excessive permanent set or distortion of soft packages are not encountered. Also, dyeing of the knit tube can be effected very economically and with a high degree of uniformity. Thus even with threads or yarns of hard textile fibers, which could be fed from packages, the advantages of dyeing are still retained. It should be noted that with certain yarns the temperature of dyeing may be sufficiently high to effect some heat setting of the yarn. Therefore, even in the case of yarns which could be practically fed from the customary bobbins or packages, the present invention presents advantages in quality and, in many cases, in cost of dyeing. As a result, even in the case of such yarns, the present invention is often advantageous and is included in a broader aspect of the present invention. Of course from the standpoint of apparatus, the feeding mechanisms are not ordinarily concerned with the exact nature of the yarn fed, and even in the process aspect of the present invention the broader claims are not to be considered as limited to special types of yarns which are difficult or impossible to feed satisfactorily without using the present invention. However, in more specific aspects such yarns are included and there the advantages of the present invention are most marked.

In considering the apparatus aspect of the present invention, in its broadest terms all that is necessary is that there be a source of the yarn tubes adjacent to the feed point of the fabric making machine, and the use of the unraveled yarn from the end of the tube presented will in many cases be sufficient to pull up the tube from its container, and only rudimentary precautions of rollers or other guide means are needed in such a case. However, in some cases this can result in the tube being pulled out faster than the fabric forming machine is using the thread unraveled from the end thereof, and this can cause the tube to jam or the unraveled thread to snarl. This is particularly likely to happen with elastic threads which are not very smooth, such as for example core spun elastic yarn. Therefore, in a preferred and more versatile form of the present invention, means are provided to feed a short predetermined length of the tube, the feeding means being controlled or a feeding cycle initiated by the unraveling of the tube back to a certain point. This insures that there is no chance of the tube getting away from the feed and being pulled out too fast and assures against malfunction even with the most difficult yarns to be handled. Because, as will be described below, very simple, reliable and cheap feeding mechanisms are possible, it is often desirable to utilize the preferred modification even with tubes of yarn which could be handled without the special period feeding of predetermined lengths of tube. In its broadest aspects, of course, the present invention is not limited to the preferred modification, but in more specific aspects this is included.

It will be obvious that the present invention does not require in all cases that the mechanism for feeding the tube, or presenting an edge to be unraveled at the proper point, be a permanent or fixed part of the fabric making machine. On the contrary, the feed may be portable and moved from one machine to another. Such a portable form will be described in more detail below, but of course the invention is not limited to it and, strictly speaking, from the standpoint of the fabric making machine, which is being fed yarn from the unraveling of the end of a tube, it makes no difference to the machine whether the tube is presented at the proper point by

mechanisms which are a fixed part of the machine or which are portable.

The advantages of dyeing in tube form, which have been mentioned above and which make the present invention of particular importance with yarns which have to be dyed, also permit readily and cheaply certain special effects which are not so readily achieved or so economically achieved with yarns dyed in skein or continuous form. Certain special fabrics require a variegated effect, that is to say, the thread may be dyed different colors or different shades of the same color which vary periodically along the thread to produce in the fabric a special variegated pattern. It is comparatively easy to dye these variegated shades in tube form, and so this special type of yarn or fabrics made therefrom constitute a field in which the present invention presents important advantages.

BRIEF DESCRIPTION OF THE DRAWINGS

FIG. 1 is an isometric view, diagrammatic in nature, of a loom with a feeding mechanism according to the present invention;

FIG. 2 is a top elevation of the feeding mechanism;

FIG. 3 is a side view of the mechanism; and

FIG. 4 is an electrical diagram of the feeding mechanism.

DESCRIPTION OF THE PREFERRED EMBODIMENT

In FIG. 1 the preferred form of tube feeding mechanism is shown, with the automatic feeding eliminated in order to avoid confusion in the drawing, the feeding mechanism being shown in FIGS. 2 and 3. Warp threads 1 from a suitable beam 2 pass through two sets of heddles 5 and 6, which in the conventional manner produce alternating sheds, and the woven fabric 3 is finally taken up on the take up roll 4. The loom is shown diagrammatically in order to avoid confusing the drawings with details which are not changed by the invention. A bullet shuttle is shown at 7 which catches the weft thread 8 in the normal manner. This thread or yarn ravel off from the end of a tube 10 and is under uniform and generally negligible tension.

The tube is folded in a container 16, which constitutes a feed reservoir, and passes up over a guide roll 9 between two feed rolls 11. In FIG. 1 the details of controls of these rolls are not shown, but in FIGS. 2 and 3 they are set forth. It will be seen in FIG. 3 that the tube 10 passes between a metallic bracket 13 which is grounded, and a finger 12 is connected to the other side of a low control voltage, as can be seen in the wiring diagram in FIG. 4. When the tube is between the finger 12 and the bracket 13, it acts, of course, as an insulator and so, as can be seen from FIG. 4, the motor driving the rolls 11, (not shown in FIGS. 1 to 3), does not turn. As the loom operates, the loom shuttle 7 pulls successive lengths of the thread or yarn 8 through the sheds as they are formed to produce the conventional picks.

As the thread unravels from the end of the tube 10, presently a point is reached where the tube is no longer between the finger 12 and the bracket 13. The finger then drops by its own weight, contact is made through a relay 17, (FIG. 4), and the feed rolls 11 turn, advancing a portion of the tube, which lifts up the finger 12. However, as the relay 17 is a normal locking relay, the rolls 11 continue to turn until a full turn causes a cam 14 on the shaft of one of the rollers to open a microswitch 15. This is clearly shown on FIG. 3. The microswitch unlocks the relay 17 in the conventional manner for a locking relay and the rolls stop. The continued operation of the loom then continues to unravel the thread 8 from the advanced end of the tube until once again the tube is unraveled past the finger 12, when the sequence of operations described above is repeated.

It will be seen that since there is no significant back tension from the unraveling of the tube, it is a matter of indifference exactly how long a piece of tube is advanced, and it is unnecessary to provide a precise synchronous drive with a loom drive. Without intending to limit the invention in any way, a

typical loom operation may result in advancing about 3 inches of tube at a time.

It will be seen that the tube feeding mechanism is extremely simple and compact, and in the case of looms or other machines requiring more than one kind of yarn, for example yarns of different colors, several feeding mechanisms may be arranged side by side or in any other configuration so that the tubes of the different yarns are presented at the proper points to the fabric making machine. The loom illustrated in FIG. 1 is in purely diagrammatic form, showing only the elements necessary to an understanding of the feed of yarn which forms the subject matter of the present invention. The means for moving the shuttles 7, beating up picks and the like are not shown as they are in no way changed by the present invention.

15 The loom is, of course, also typical only of one type of fabric making machine, and the invention is applicable to any such machine which utilizes yarn or yarns from an external source, for example, a catch thread loom, knitting machine, and the like.

The more specific modifications of the present invention can use any mechanism for advancing periodically a length of tube. The electrically controlled advancing mechanism which is illustrated in the drawings is simple, reliable and cheap, and may be considered a preferred form of the present invention.

25 However, any other means may be used. For example, the amount of tube fed may be controlled by electric eyes or by any other means which stops the advance after the desired amount has been obtained.

30 Where the yarns are of suitable types, it is possible to use a simplified feed mechanism in which the rolls 11 and their drives are eliminated, the tube being pulled up from its supplying container by the pull of the yarn 8 as it is unraveled. This simplified feed mechanism does not give as great protection against pulling out the tube too fast and possible snarling. Therefore, for many purposes the preferred specific modification which is shown in the drawings will be advantageous and, of course, is more versatile, as it can be used with yarn having characteristics such that the simplified mechanism would not be suitable.

40 We claim:

1. A mechanism for feeding yarn to a fabric making machine utilizing at least one yarn from an external source, which comprises:

a. an external source suitable for storing a continuous, folded, knitted tube of the yarn to be used; and

b. means for feeding an end of the tube to a point on the fabric making machine where yarn is to be supplied, said means advancing predetermined lengths of tube to the point adjacent the fabric forming machine, the advancing means being provided with means for starting the advancement when the tube has been unraveled to a predetermined point and for stopping the advancement after the predetermined length of tube has been advanced whereby the yarn is unraveled from the tube as the fabric making machine operates and uses the yarn, whereby the fabric making machine receives yarn feed at uniform low tension.

55 60 2. A mechanism according to claim 1 in which the tube passes between electrical contacts, one of which is movable, whereby the tube insulates the contacts until the tube has been unraveled back to the point where the contacts can close, and means for advancing tube actuated by the closing of the contacts, said advance means being provided with stopping means after a predetermined advance.

65 70 3. A mechanism according to claim 2 in which the advancing means comprises a pair of rolls, an electric motor for driving them, contacts between which the predetermined length of tube moves, one of the contacts being movable by gravity to close a circuit with the other contact when the tube is unraveled back to the predetermined length, locking relay means actuated by said contacts to start the motor turning, and means operated by a predetermined rotation of the motor for unlocking and resetting the locking relay means.

4. A mechanism according to claim 3 in which the relay unlocking and resetting means comprise a cam on a shaft turned by the motor and a microswitch cooperating therewith to unlock and reset the locking relay means.

5. A process for feeding a fabric making machine with at least one externally supplied yarn, which comprises presenting to the machine a knitted tubular tube of the yarn to be used by the machine by advancing a predetermined length of tube, permitting the machine to feed itself yarn unraveled from the end of the tube and repeating the advancing of the tube when the unraveling of the yarn has unraveled the predetermined

length of tube which was advanced.

6. A process according to claim 5 in which a plurality of yarns are fed to the fabric making machine, the yarns having differing characteristics.

7. A process according to claim 6 in which the differing characteristics of the yarn are different colors.

8. A process according to claim 5 in which the yarn is elastic yarn.

9. A process according to claim 8 in which the elastic yarn is 10 core spun yarn.
